UNITED STATES PATENT OFFICE.

THEODORE C. MOLSDALE, OF CHATTANOOGA, TENNESSEE.

SEESAW.

Application filed December 18, 1926. Serial No. 155,614.

This invention relates to seesaws and particularly to a rocking device which can be employed as a toy in a house or as an apparatus on play grounds and the like.

It is an object of this invention to produce a seesaw which will not operate to degrees of danger in its movement while rocking and which will be prevented from lateral displacement or other movements that would injure or endanger the lives of the occupants.

It is a further object of this invention to produce a seesaw which can be easily mounted or entered in order that children in entering or leaving the seesaw will not be injured, the said device being further provided with means for preventing its being tilted laterally or from rocking beyond the zones of safety.

It is a further object of this invention to provide a seesaw which will prove efficient and satisfactory in use and at the same time comparatively inexpensive to manufacture.

With the foregoing and other objects in view, the invention consists in the details of construction, and in the arrangement and combination of parts to be hereinafter more fully set forth and claimed.

In describing the invention in detail, reference will be had to the accompanying drawings forming part of this application wherein like characters denote corresponding parts in the several views, and in which—

Figure 1 illustrates a view in side elevation of a seesaw embodying the invention;

Figure 2 illustrates a plan view thereof;

Figure 3 illustrates a sectional view on the line 3—3 of Figure 1;

Figure 4 illustrates an end view of the said seesaw;

Figure 5 illustrates a plan view of the central part of the structure; and

Figure 6 illustrates a sectional view thereof.

The base 10 of the seesaw may be of any appropriate type that is to say, it may consist of a scantling or beam resting on a foundation or it may, as in the present embodiment of the invention, consist of a horizontally disposed plate or board 11 with supports 12 at the edges thereof and the said supports may be provided with legs or other appropriate foundations such as 13 but the inventor does not wish to be limited with respect to the type of mountings employed. It is here shown that vertical guides 14 are employed and these guides are located at the longitudinal center

of the device. Springs 15 are supported on blocks 16 and the upper ends of the springs bear against and are anchored to the rocking or oscillating element 17 of the seesaw and they tend to stabilize the movement. The spring slightly retards the freedom of movement but causes a smoother action which may be desirable under certain conditions of use.

The rocking element, in the present embodiment of the invention, comprises a board 65 preferably wider than its support 11 as it has been found in practice that the clearance of the rocking element beyond the edges of the support presents means which will prevent children when entering or leaving the seesaw 70 or while it is in operation from getting their fingers between the rocking element and its support and thus the device can be made safer and without liability of injuring the users. While the springs have been found 75 a desirable feature they may, under certain conditions of use, be omitted without materially affecting the efficient and satisfactory operation of the device.

As shown in Figure 2 the rocking element 80 or board is curved and it may be held in the shape in which it is shown in Figure 1 by the longitudinally extending side elements or braces 18 and they may be secured to the board at their ends or they may be supplied 85 with fastenings 19 such as screws, nails or the like which are anchored in plates or strips 19 secured to the board in any appropriate way, but these are details of construction which may be changed.

A seat 20 of appropriate design may be secured near each end of the rocking element or board and a foot rest 21 may be provided for each seat in order that the occupant of the seat may be braced and supported through 95 the use of the foot rest.

The users of the seesaw may enter by mounting the rocking element where it is in engagement with the base or support and the user may then move toward either end as the 100 rocking element will yield under the weight of the occupant walking toward one of the seats.

As a means for preventing the rocking element from tilting laterally, diagonally disposed braces 22 and 23 are provided at each side and the upper ends of the braces are in contact above the longitudinal center of the frame. The braces of one side are connected to the braces of the other side by a block or 110

strip 24 and the braces and element 24 are appropriately secured together by fastenings 25 such as nails or the like.

The braces 22 and 23 may be connected to 5 the sides of the base through the use of filling blocks such as 16, but other means may be provided for accomplishing this result. The strip 24 acts as a means for limiting the 10 rocking motion of the element 17, by reason of the fact that the braces 18 will encounter the said strip when undue rocking motion is imparted to the member 17.

As the operation of the device has been described in connection with the description of 15 the various parts of the device, a résumé of the operation is believed unnecessary.

I claim:

1. In an amusement device, a base, an oscillatable element thereon wider than the 20 base and projecting from the edges of the base, said oscillatable element being upwardly curved at its ends, braces connecting the upturned portions for maintaining them in certain positions, seats on the oscillatable element near its ends, means at the edge of the 25 said element for preventing lateral movement thereof, and means for limiting the oscillatory movement of the said element.

2. In an amusement device, a base, an 30 oscillatable element having its ends upward-

ly curved and wider than the base, means connecting the upwardly curved portions of the oscillatable element together for bracing the same and maintaining it rigid, seats near the ends of the element, foot rests on 35 the said element below the seats, and means for preventing lateral movement of the element.

3. In an amusement device, a base, an oscillatable element thereon having its ends 40 upwardly curved and wider than the base, means for connecting the upwardly curved portions of the oscillatable element thereon together for bracing the same and maintaining it rigid, seats near the ends of the element, foot rests on the said element below 45 the seats, and upstanding braces at the sides of the element for preventing lateral movement of the element and having means for limiting the oscillatory movement of the said element.

4. In an amusement device, an oscillatable element comprising a strip of material bowed to form a rocker, braces having their ends anchored to the said element near its end for 50 holding the strip in a bowed shape, seats on the said oscillatable element, and a base narrower than the oscillatable element on which said oscillatable element is supported.

THEODORE C. MOLSDALE.
